CLAIM

U.S. PATENT DOCUMENTS

The ornamental design for a keyboard for use with a
handheld electronic device, as shown and described.

DESCRIPTION

FIG. 1 is a front elevation of a keyboard in accordance with
the design; the broken line drawing of a device in this view
is for illustrative purposes only and forms no part of the
claimed design;

FIG. 2 is a right side elevation of a keyboard in accordance
with the design; the broken line drawing of a device in this view
is for illustrative purposes only and forms no part of the
claimed design; and,

FIG. 3 is a left side elevation of a keyboard in accordance
with the design; the broken line drawing of a device in this view
is for illustrative purposes only and forms no part of the
claimed design.
